J. W. BOARD.
CROSSTIE.
FILED MAY 12, 1922.

Fig. 1.

UNITED STATES PATENT OFFICE.

JASON W. BOARD, OF BUFFALO, WEST VIRGINIA.

CROSSTIE.

Application filed May 12, 1922. Serial No. 560,403.

To all whom it may concern:

Be it known that I, JASON W. BOARD, a citizen of the United States of America, residing at Buffalo, in the county of Putnam 5 and State of West Virginia, have invented new and useful Improvements in Crossties, of which the following is a specification.

The object of the invention is to provide a simple and efficient construction of cross tie for railway track rails of the type wherein a metal frame is employed as a support for blocks of wood or similar material constituting the seats for the rails, to the end that the requisite strength and resilience of 10 the tie may be secured with the minimum use of wood; and with this object in view the invention consists in a construction and combination of parts of which a preferred embodiment is shown in the accompanying 15 drawings, wherein:—

Figure 1 is a perspective view of a tie embodying the invention.

Figure 2 is a view of the base.

Figure 3 is a transverse sectional view 25 taken in the plane of one of the clamps.

Figure 4 is a detail view of one of the clamp members.

The tie consists essentially of a channeled base 10 having a central shallow portion of 30 transversely arcuate shape and terminal seat portions of rectangular shape for bearing or seat blocks 11 of wood or similar material which are held against longitudinal outward displacement by stops 12 cast upon or rigidly attached to the floor of the base at its 35 extremities. The central shallow portion is elevated above the plane of the bottom of the block seats, the bottoms of which are curved upwardly and blend into the bottom 40 of the shallow portion at a sharp angle, as clearly illustrated in Figures 1 and 2 of the drawings. Clamps 13 are engaged with the base and embrace the blocks 11 preferably inside and outside of the plane of each rail 45 14 for locking the blocks in their proper positions on the base.

The block seats are preferably roughened or serrated as indicated to frictionally resist longitudinal movement of the blocks 50 with relation to the base, and the side walls of the base are offset at intervals to form keepers 15 for the reception of the legs of the clamps which are thereby anchored to the base, each clamp consisting of separate 55 members 13^a of angular form having their

shanks provided at their lower ends with enlarged heads 16 forming shoulders to engage the lower edges of the keepers, and having at their upper ends inwardly directed arms 13^b overlying the upper side of the block and 60 provided at their extremities with upturned perforated ears 13^c which are engaged by the clamp bolts 17. The clamp bolts are preferably equipped with spring washers 18 to cushion vibration and minimize strain 65 upon the parts to reduce the likelihood of fracture under service conditions. The bottom or floor of the base is provided with suitable openings 19 to permit of the engagement of the headed or enlarged lower 70 ends of the clamp shanks therewith, the members of each clamp being engaged with the base before the block is slid into place, so that when the parts are assembled the block serves as a means of preventing disengagement of the clamp members from the 75 base while the clamps serve to lock the blocks in their proper positions on the base. The rails are secured to the blocks by the ordinary spikes 20 or any preferred equivalent thereof.

Having described the invention, what is claimed as new and useful is:—

1. A tie having a channeled base, blocks seated in the channel at the extremities of the base to form a bearing for the track rails, and clamps engaging the base and engaged with the blocks for securing them in their proper positions with relation to the base, each clamp having separate members 85 interlocked at their lower ends with the base and arranged at their upper ends in overlapping relation with the block, and a bolt engaging the upper ends of said members.

2. A tie having a channeled base, blocks seated in the channel at the extremities of the base to form a bearing for the track rails, and clamps engaging the base and engaged with the blocks for securing them in their proper positions with relation to the 100 base, the side walls of the base being offset to form keepers, and the clamps consisting of separable side members having headed lower ends for interlocking engagement with said keepers and having their upper ends connected by adjusting bolts.

3. A tie having a channeled base, blocks seated in the channel at the extremities of the base to form a bearing for track rails, and clamps engaging the base and engaged 110

with the blocks for securing them in their proper positions with relation to the base, the side walls of the base being offset to form keepers, and the clamps consisting of 5 separable side members having headed lower ends for interlocking engagement with said keepers and having inwardly directed arms

overlying the upper side of the block, the said arms being provided at their extremities with upturned ears, and bolts engaging 10 said ears.

In testimony whereof I affix my signature.

JASON W. BOARD.
